Primary Examiner — Maria J. Edwards

(57) **CLAIM**

The ornamental design for a hand warmer pouch as shown and described.

DESCRIPTION

FIG. 1 is a front, left and top perspective view of a hand warmer pouch showing our new design;

FIG. 2 is a rear, right and bottom perspective view thereof;

FIG. 3 is a front elevational view thereof;

FIG. 4 is a rear elevational view thereof;

FIG. 5 is a right view thereof;

FIG. 6 is a left view thereof;

FIG. 7 is a top plan view thereof;

FIG. 8 is a bottom plan view thereof;

FIG. 9 is an enlarged view of a portion labeled as "9" on FIG. 1;

FIG. 10 is an enlarged view of a portion labeled as "10" on FIG. 1;

FIG. 11 is a front, left and top perspective view, showing the hand warmer pouch in an inside out configuration 2;

FIG. 12 is a rear, right and bottom perspective view thereof, showing in configuration 2;

FIG. 13 is a front elevational view thereof, showing in configuration 2;

FIG. 14 is a rear elevational view thereof, showing in configuration 2;

FIG. 15 is a right view thereof, showing in configuration 2;

FIG. 16 is a left view thereof, showing in configuration 2;

FIG. 17 is a top plan view thereof, showing in configuration 2; and,

FIG. 18 is a bottom plan view thereof, showing in configuration 2.

The long dash-short dash broken lines demarcate enlarged views and form no part of the claim. The evenly dashed broken lines illustrate portions of the hand warmer pouch and form no part of the claimed design.

1 Claim, 18 Drawing Sheets
